(57) **CLAIM**

The ornamental design for a pen holder, as shown and described.

DESCRIPTION

FIG. 1 is a front-left-top perspective view of a first embodiment of a pen holder according to my new design; FIG. 2 is a front elevational view thereof, wherein the rear elevational view is a mirror image of the front elevational view;

FIG. 3 is a top plan view thereof;

FIG. 4 is a bottom plan view thereof;

FIG. 5 is a left side elevational view thereof;

FIG. 6 is a right side elevational view thereof;

FIG. 7 is front environmental view thereof mounted to a coordinate input device;

FIG. 8 is front environmental view thereof mounted to a coordinate input device and holding a pen;

FIG. 9 is a front-left-top perspective view of a second embodiment of a pen holder according to my new design;

FIG. 10 is a front elevational view thereof, wherein the rear elevational view is a mirror image of the front elevational view;

FIG. 11 is a top plan view thereof;

FIG. 12 is a bottom plan view thereof;

FIG. 13 is a left side elevational view thereof;

FIG. 14 is a right side elevational view thereof;

FIG. 15 is front environmental view thereof mounted to a coordinate input device; and,

FIG. 16 is front environmental view thereof mounted to a coordinate input device and holding a pen.

The dashed broken lines in the drawings show portions of the pen holder that form no part of the claimed design. The dot-dot-dash broken lines in the drawings indicate environmental subject matter and form no part of the claimed design.
